UNITED STATES PATENT OFFICE.

MICHAEL J. HOLLENBECK, OF GLOVERSVILLE, NEW YORK.

MITTEN.

1,417,323.

Specification of Letters Patent. Patented May 23, 1922.

Application filed October 7, 1920. Serial No. 415,260.

To all whom it may concern:

Be it known that I, MICHAEL J. HOLLENBECK, a citizen of the United States, and a resident of Gloversville, in the county of Fulton and State of New York, have invented a new and Improved Mitten, of which the following is a full, clear, and exact description.

The invention relates to mittens made of one piece of a fabric material, such, for instance, as shown and described in the Letters Patent of the United States, No. 83,800, granted to George Topping on November 3, 1868.

15 The object of the invention is to provide a new and improved mitten made of a single piece of fabric material and arranged to insure a proper fit on the hand of the user particularly at the wrist.

20 Another object is to provide a desired fullness at the junction of the base of the thumb with the front of the body portion thus allowing the desired movement of the thumb without danger of binding at or straining the thumb seam.

25 Another object is to render the mitten seamless at the outer edge, thus heightening the appearance of the mitten and avoiding binding at or tearing at the outer side as is 30 so frequently the case with mittens having side seams constructed in the lines of the patent above referred to.

Another object is to permit the user to readily pass the hand into the mitten.

35 With these and other objects in view, the invention consists of certain novel features of construction, as hereinafter shown and described and then specifically pointed out in the claims.

40 A practical embodiment of the invention is represented in the accompanying drawings forming a part of this specification, in which similar characters of reference indicate corresponding parts in all the views.

45 Figure 1 is a plan view of the front of the mitten;

Figure 2 is a similar view of the back of the mitten;

Figure 3 is a plan view of the front of the mitten with the thumb shown bent back;

Figure 4 is a plan view of the blank from which the mitten is produced; and

Figure 5 is a perspective view of a portion of the mitten blank with the sides partly sewed together at the base of the thumb.

The mitten is formed from a single blank of a suitable fabric or other flexible material, shaped to provide a middle portion 10 and two side portions 11 and 12 adapted to be folded along the lines 13 and 14 to form 60 the front of the mitten, while the middle portion 10 forms the back of the mitten. The forward part of the side portion 11 forms with the corresponding forward part of the middle portion 10 the covering for the 65 fingers. The rear part 16 of the side portion 11 is narrower than the forward part and forms with the side portion 12 the palm of the mitten. From the forward part of the side portion 11 extends integrally the 70 inner thumb member 17 while the outer thumb member 18 extends forwardly from the side portion 12.

In making the mitten the thumb member 17 is bent forward to join along its edges 75 with the edges of the thumb member 18. The bases of the thumb members 17 and 18 are provided with shoulders 19 and 20 at the outer edges of the side portions 11 and 12, and these shoulders 19 and 20 are 80 disposed opposite each other (see Figure 4).

The rear portion of the blank is extended beyond the wrist line 21 to provide a portion 22 doubled up inwardly to form a hem 23. The side edges of the portion 22 are flared 85 outwardly, as plainly indicated in Figure 4, and hence the hem 23 forms a flaring mouth for the body.

After the blank has been cut then the parts are folded along the lines 13 and 14 with the reverse face of the fabric material outside. The thumb members 17 and 18 are next moved into overlying position, after which the parts are fastened together along the overlying edges by a single row of stitches 90 25 to form the mitten. The row of stitches 25 overlies the shoulders 19 and 20 and hence the shoulder 19 is sewed to the back 10 at the junction of the edges of the back and the thumb member 18 to widen the base 95 of the thumb at the outer side. In a like manner the shoulder 20 is sewed by the stitches 25 to the side portion 11 at the junction of the edges of the narrow portion 16 and the thumb member 17 to enlarge the 100 base of the thumb at the inner side thereof, that is, approximately at the upper middle portion of the palm, as plainly indicated in Figure 1. The hem 23 is formed by doubling up the portion 22 and fastening the same to 105 110

gether by a row of stitches 26. The mitten is then turned inside out and is ready for use.

It will be noticed that by the use of the shoulders 19 and 20 the base of the thumb is widened to provide the desired fullness at the junction of the base of the thumb with the body of the mitten thereby providing an enlarged entrance for the thumb of the wearer and allowing the desired movement of the wearer's thumb without danger of binding at or straining the thumb seams. It will also be noticed that by this arrangement the portion of the seam at the palm 15 extends along the median line of the front of the mitten from the shoulders 19 and 20 to the rear edge of the mitten, as plainly indicated in Figures 1 and 3. By reference to Figure 3 it will be noticed that by projecting the inner portion of the base of the thumb inward towards the middle of the palm the thumb seam is relieved of strain when the user moves the thumb inward or outward, as in handling objects, owing to 20 the strain being exerted along the material of the mitten in the direction of the length of the inner portion 17 of the thumb and that of the forward part of the front. In practice, the forward edges of the middle and 25 side portions 10 and 11 of the blank are rounded off and hence an unbroken outer edge is provided at the mitten along the line 13 thus eliminating a seam at this outer edge and thereby heightening the appearance of 30 the mitten at the same time reducing the possibility of tearing along this edge owing to the absence of a seam. By providing the flaring mouth at the wrist the user can readily pass the hand into the mitten and at the 35 same time the mitten fits snugly around the wearer's wrist.

Having thus described my invention, I claim as new and desire to secure by Letters Patent:

45 1. A one-piece mitten, comprising a back, a front, a thumb made in two parts, one of the thumb parts having an integral shoulder at the outer edge of its base and the other thumb part having an integral shoulder at 50 the inner edge of its base, and a continuous row of stitches connecting the back with the front and connecting the edges of the thumb parts with each other, the shoulders of the thumb parts being fastened by the stitches 55 to the corresponding edges of the front and back to provide an enlarged base for the thumb.

2. A mitten blank formed of one piece of material and comprising a middle portion 60 and side portions, of which the middle portion is adapted to form the back of the mitten and the side portions are adapted to form the front of the mitten, one of the said side portions being reduced in width at its 65 rear palm and wrist portion, and having a

rearwardly extending thumb member alongside the reduced portion, and the other side portion having a forwardly extending thumb member, the outer edges of the said side portions of the blank having shoulders at the 70 bases of the said thumb members.

3. A new article of manufacture consisting of a mitten formed of a single blank of material and comprising a middle portion and side portions of which the middle portion is adapted to form the back of the mitten, and the side portions adapted to form the front of the mitten, the blank being folded at the juncture of the middle portion with the side portions, with the front portion overlying the back portion, one of said side portions being reduced in width at its rear palm and wrist portion and having the remaining portion of the width thereof cut to provide a thumb member extending along 80 the reduced portion and curved slightly outwardly and formed with a shoulder at the juncture thereof with the side portion at the base of the thumb member and on the outer edge of the side portion, and the other side 90 portion having a forwardly extending tapered thumb member terminating short of the tips of the middle and other side portion, the second thumb member extending in the opposite direction with respect to the 95 direction of extent of the first thumb member and formed with a shoulder at the juncture thereof with the corresponding side portion and at the outer edge of the latter, said shoulders facing in opposite directions. 100

4. A new article of manufacture consisting of a mitten formed of a single blank of material and comprising a middle portion and side portions of which the middle portion is adapted to form the back of the mitten, and the side portions adapted to form the front of the mitten, the blank being folded at the juncture of the middle portion with the side portions with the front portion overlying the back portion, one of said side portions being reduced in width at its rear palm and wrist portion and having the remaining portion of the width thereof cut to provide a thumb member extending along 110 the reduced portion and curved slightly outwardly and formed with a shoulder at the juncture thereof with the side portion at the base of the thumb member and on the outer edge of the side portion, and the other side portion having a forwardly extending tapered thumb member terminating short of the tips of the middle and other side portion, the second thumb member extending in the opposite direction with respect to the 115 direction of extent of the first thumb member and formed with a shoulder at the juncture thereof with the corresponding side portion and at the outer edge of the latter, said shoulders facing in opposite directions. 120

125

130

outwardly and the adjacent end doubled to form a hem suitably stitched, the outer edges of the side portions at the palm and wrist being joined at approximately the middle 5 portion of the palm, the first named thumb portion being turned back in the direction of extent of the second named thumb portion and the shoulder thereof sewed to the back

at the juncture of the edges of the back and other thumb member and the other shoulder 10 being secured to the other side portion at the juncture of the edges of the narrow portion and the adjacent thumb member to enlarge and widen the base of the thumb at the outer and inner sides.

MICHAEL J. HOLLENBECK.
